UNITED STATES PATENT OFFICE

116,334

DESIGN FOR A BELT BUCKLE

Jacob Lewis Bibula, New York, N. Y.

Application July 15, 1939, Serial No. 86,036

Term of patent 3½ years

To all whom it may concern:

Be it known that I, Jacob Lewis Bibula, a citizen of the United States of America, residing at 222 West 37th Street, county of New York, and State of New York, have invented a new, original, and ornamental Design for a Belt Buckle, of which the following is a specification, reference being had to the accompanying drawing, forming part thereof.

Fig. 1 is a plan view of a belt buckle showing my new design.

Fig. 2 is an edge view thereof.

I claim:

The ornamental design for a belt buckle, substantially as shown.

JACOB LEWIS BIBULA.
